G. A. KRAUSE

PROCESS OF AND APPARATUS FOR EVAPORATING LIQUIDS

Filed June 19, 1920

INVENTOR:
Georg A. Krause

By *Otto Munk*

his ATTORNEY.

UNITED STATES PATENT OFFICE.

GEORG ALEXANDER KRAUSE, OF MUNICH, BAVARIA, GERMANY, ASSIGNOR, BY MESNE ASSIGNMENTS, TO AMERICAN LURGI CORPORATION, OF NEW YORK, N. Y., A CORPORATION OF NEW YORK.

PROCESS OF AND APPARATUS FOR EVAPORATING LIQUIDS.

Application filed June 19, 1920. Serial No. 390,302.

(GRANTED UNDER THE PROVISIONS OF THE ACT OF MARCH 3, 1921, 41 STAT. L., 1313.)

To all whom it may concern:

Be it known that I, GEORG ALEXANDER KRAUSE, citizen of Germany, residing at Munich, Bavaria, Germany, have invented 5 certain new and useful Improvements in a Process of and Apparatus for Evaporating Liquids (for which I have filed applications in Germany, on July 11, 1917; Austria, July 6, 1918; Switzerland, July 9, 10 1918; Holland, July 9, 1918; Sweden, July 11, 1918; Norway, July 11, 1918; Denmark, July 11, 1918; Hungary, July 13, 1918; Great Britain, September 2, 1919; and France, July 17, 1918); and I do hereby declare the following to be a full, clear, and exact description 15 of the invention, such as will enable others skilled in the art to which it appertains to make and use the same.

My invention relates generally to the evaporation 20 of liquids by subjecting such liquids to atomization and the action of a drying current, and more specifically the invention is concerned with the prevention of the formation of a vacuum at the points where 25 the drying current issues into the treating chamber.

One well known method of evaporating liquids consists in feeding such liquids to a centrifugal device revolving at high speed 30 in an evaporating chamber wherein the liquid is atomized and spread in a stratum or mist of suitable shape and direction, such as a horizontal or substantially horizontal stratum, and passing current of drying medium through the mist.

In the practice of this method it was found 35 that a partial vacuum or regions of reduced pressure frequently formed at or adjacent to the liquid discharging or atomizing points. The atomized liquid has a tendency to be drawn into such regions of partial vacuum and condense on the atomizing orifices. Moreover, some of the dried substance will be drawn into these regions of reduced pressure, 40 tending to choke the nozzles or form a crust on the centrifugal apparatus. It will be readily seen therefore that the creation of such partial vacuum results in destroying the desired movement of the atomized fluid thus 45 detrimentally affecting the drying action. The principal object of my invention is to provide an improved method and apparatus by means of which the disturbance in the

desired shape or movement of the atomized fluid is prevented. This is accomplished by 55 balancing the reduced pressure that arises around the atomizing orifices preferably through the agency of the drying medium which is deflected or forced towards the points at which the fluid is atomized. 60

In accordance with the present embodiment of the invention it is contemplated that the atomized liquid move in the chamber in a horizontal or substantially horizontal stratum. Obviously, however, the shape of 65 the stratum or the direction in which the atomized liquid is moved may be varied without departing from the spirit of the present invention.

The invention is illustratively exemplified 70 in the accompanying drawing in which Fig. 1 is a somewhat diagrammatic view of the apparatus as at present employed in the practice of the method; Fig. 2 is a similar view embodying one form of my invention, 75 and Fig. 3 is a similar view embodying a second form of my invention.

Referring to Fig. 1 of the drawing, *a* is the evaporating chamber wherein a centrifugal disc *b* is rotated at high speed by any suitable 80 motor *c*. The liquid to be evaporated is fed to the disc *b* through a vertical feed pipe *d*. The drying medium, either hot air or any other suitable gaseous medium, is fed through the pipe *d* and issues into the chamber *a* out of the openings *e*.

In using an apparatus such as described and illustrated in Fig. 1, it was found that by the issuance of the liquid into the chamber *a* through the openings in disc *b*, there 90 was a tendency for the formation of a partial vacuum adjacent said openings in disk *b* whereby the horizontal or substantially horizontal movement of the stratum of mist formed by the revolving disc *b* was disturbed. 95 This disturbance in direction is due to the fact that, due to the formation of regions of reduced pressure adjacent to the orifices in disc *b*, particles of atomized fluid are drawn towards the orifices of disc *b* and obstruct them. Due to this the atomized liquid will no more be spread into the chamber *a* in a substantially horizontal stratum but particles of the fluid will be shot in all directions, upward and downward and some imperfectly dried particles will flow in the di- 100 105

rection indicated by the arrows and settle on the walls of the chamber and moisten the latter.

By means of my invention I balance the partial vacuum that would be created around the atomizing orifices by deflecting the entering air stream towards the atomizer thus balancing the pressure thereat and preventing the creation of eddies and cross-currents normally attending the introduction of the air jets and irregularly distributed mist and consequently the desired horizontal or substantially horizontal layer or stratum of atomized liquid is undisturbed as to direction. The essence of my invention consists in so directing the drying medium issuing from the openings *e* that the disturbing tendency above described is neutralized.

In the form of Fig. 2 I provide adjacent the outlets *e* a number of guides *f* which direct a part of the heating medium issuing from the outlets *e* upwardly under the layer of mist formed by the centrifugal disc *b*, whereby part at least of the air is directed towards the atomizing point of the fluid, will balance the pressure at such point and thus insure the formation of a substantially horizontal stratum.

Fig. 3 shows a form of the invention in which the lower face of the disc *b* is provided with fan blades or ribs *g*, which suck a part of the drying medium upwardly and by hurling the same horizontally or substantially so permit the stratum of atomized fluid to maintain its desired horizontal direction.

I claim:—

1. In a method of evaporating liquids including the discharge of a liquid from a vessel under such conditions as to form a substantially horizontal stratum of mist in a drying medium, the step of minimizing the formation of a zone of reduced pressure adjacent the points of discharge, which consists in directing and maintaining a flow of the said medium into the region in which the zone of reduced pressure would normally be formed.

2. In a method of evaporating liquids including the discharge of a liquid by centrifugal force from a plurality of orifices of a vessel to form a substantially horizontal stratum of mist and the discharge of a drying medium below the stratum of mist, the step of minimizing the formation of a zone of reduced pressure adjacent the points of discharge of liquid from the vessel, which

consists in directing and maintaining a flow of the said drying medium upwardly into the region in which the zone of reduced pressure would normally be formed.

3. In apparatus for evaporating liquids including a vessel operated on the principle of centrifugal force for discharging a liquid to form a substantially horizontal stratum of mist and means for minimizing a zone of reduced pressure adjacent the points of discharge, said means being operative to direct and maintain a flow of the surrounding atmosphere into the region in which the zone of reduced pressure would normally be formed.

4. In apparatus for evaporating liquids, an atomizer including a vessel having discharge orifices for forming a substantially horizontal stratum of mist, means disposed below the atomizer for supplying a drying medium and means for minimizing the formation of a zone of reduced pressure adjacent the discharge orifices, said means being operative to direct and maintain a flow of the drying medium upwardly into the region in which the zone of reduced pressure would normally be formed.

5. In apparatus for evaporating liquids, an atomizer including a vessel having discharge orifices for forming a substantially horizontal stratum of mist, means disposed below the atomizer for supplying a drying medium and means for minimizing the formation of a zone of reduced pressure adjacent the discharge orifices, said means consisting of means for positively deflecting at least a part of the drying medium into the region in which the zone of reduced pressure would normally be formed.

6. In apparatus for evaporating liquids including a vessel operated on the principle of centrifugal force for discharging a liquid to form a substantially horizontal stratum of mist and means for minimizing a zone of reduced pressure adjacent the points of discharge, said means consisting of fan blades forming part of the vessel and disposed to cause a flow of the surrounding atmosphere into the region in which a zone of reduced pressure would normally be formed.

In testimony whereof I hereunto affix my signature in the presence of two witnesses.

GEORG ALEXANDER KRAUSE.
